UNITED STATES PATENT OFFICE.

EDWARD J. VOGEL, OF SAN FRANCISCO, CALIFORNIA.

GOLF-BALL PRACTICE SUBSTITUTE.

1,363,446.

Specification of Letters Patent. Patented Dec. 28, 1920.

Application filed November 10, 1919. Serial No. 336,772.

To all whom it may concern:

Be it known that I, EDWARD J. VOGEL, a citizen of the United States, residing at San Francisco, in the county of San Francisco and State of California, have invented new and useful Improvements in Golf-Ball Practice Substitute, of which the following is a specification.

The object of the present invention is to provide a substitute for a golf ball for practising driving or hitting the golf ball, which, after being hit or driven by the golf club, will immediately return to its original position in readiness for another stroke of the golf club, and will require no teeing up.

In the accompanying drawing, Figure 1 is a vertical longitudinal section of my improved golf ball substitute, showing also in vertical section a mat used in connection therewith; Fig. 2 is a vertical section of the mat as it appears before the substitute golf ball is attached thereto; Fig. 3 is a plan view of the substitute golf ball; Fig. 4 is a horizontal sectional view on the line 4—4 of Fig. 1; Fig. 5 is a front view thereof; Fig. 6 is a sectional view on the line 6—6 of Fig. 1; Fig. 7 is a perspective view of the mat and substitute golf ball.

Referring to the drawing, 1 indicates a mat, preferably of rubber and preferably of one half of an inch in thickness. Through said mat is cut a recess hole 2 and through said hole 2 is passed a rubber tongue 3 secured at the lower side of said mat by a broad headed screw 4 countersunk in the upper part of the mat and a nut 6 screwed on said screw and countersunk in said tongue. The tongue 3 extends through the hole 2 above the mat, and, above the mat it is externally, and viewed from above, of a somewhat globular form, as shown at 7, and of the same dimensions as an average sized golf ball, being curled over, as shown at 8, and extending downward, as shown at 9, so that the globular portion 7 appears to be raised above the surface of the mat to the same height as a golf ball when teed up. The sides of the globular portion 7 of the strip taper gradually in thickness 50 to the edge, as shown at 10 in Fig. 6.

It results from this construction that the substitute golf ball, when viewed from the position of a player addressing the ball, presents an appearance sufficiently like to a golf ball to be a perfect substitute therefor in practising. The globular portion of the

strip may be formed with a brambled or dimpled surface, as desired, and will be colored white in contrast to the mat, which is colored green, to further simulate a golf ball teed up.

I preferably, although not necessarily, provide the globular portion 7 of the ball with a small protuberance 11 at the point where the club strikes the ball substitute, for two reasons:—first, to assist the player in keeping his eyes on the exact spot to be struck by the club, and, second, to strengthen the ball substitute against the impact of the club.

When the substitute ball is struck by the club, it will yield to the blow of the club, assuming the position shown in dotted lines in Fig. 1, so that the club head will pass over the strip in the natural course of its swing, the comparatively thin edges 10 of the strip straightening out to permit the club head to pass thereover. Immediately that the club head has passed over the substitute ball, and long before the player is ready for another stroke, the substitute ball will spring back to its original position.

The resistance offered by the ball substitute to the impact of the club is not more than the resistance offered by an ordinary ball to said impact.

I have found a satisfactory composition for the golf ball substitute to be 40% para rubber and the remainder of first class mineral matter, not including more than 3% sulfur, which percentage includes the sulfur in the mineral matter.

The mat forms an important, although not an absolutely necessary, feature of my invention, because it protects the tongue or stem of my improved golf ball substitute from being struck by the golf club head, with damage thereto, and early fracture thereof if the impact is repeated a sufficient number of times.

An obvious advantage of the mat is that when practising the stroke indoors, it protects the floor or carpet from the blows due to improper swings of the golf club.

I claim:—

1. A golf ball practice substitute formed of a strip of elastic material, one terminal portion of which is adapted to be attached to the under side of a mat or the like, the mat or the like being formed with a hole through which the portion of the substitute adjacent to said terminal portion can extend,

the other terminal portion of the strip being free, and the portion of the substitute adjacent to the latter terminal portion being formed to resemble, when viewed from 5 above, a golf ball.

2. A golf ball practice substitute having an upper portion somewhat resembling a golf ball, a lower portion provided with means for retaining it in position, and an intermediate self-sustaining neck-like portion 10 formed of elastic material and connected with one side only of the upper portion.

3. A golf ball practice substitute of elastic material having a self-sustaining upwardly 15 extending portion somewhat resembling,

when viewed from above, a golf ball, a lower portion provided with means for attachment to a mat, and a neck-like portion of the same material connected with one side only of the upper portion.

4. A golf ball practice substitute comprising a strip of elastic material adapted to be attached to a mat or the like, the upper portion of the strip being formed to present the appearance, when viewed from above, of a golf ball and being curled over in the direction of the strip, and being attached to the strip at the side only from which it is curled over.

EDWARD J. VOGEL.
